US0D1055974S

(12) **United States Design Patent** (10) **Patent No.:** **US D1,055,974 S**
(45) **Date of Patent:** **** Dec. 31, 2024**

(54) **ELECTRONIC DEVICE WITH GRAPHICAL USER INTERFACE**

- (71) Applicant: **Apple Inc.**, Cupertino, CA (US)
(72) Inventors: **Alan C. Dye**, San Francisco, CA (US); **Eric Lance Wilson**, San Jose, CA (US)
(73) Assignee: **Apple Inc.**, Cupertino, CA (US)
(***) Term: **15 Years**
(21) Appl. No.: **29/853,020**
(22) Filed: **Sep. 12, 2022**

Related U.S. Application Data

- (63) Continuation of application No. 29/835,975, filed on Apr. 22, 2022, now Pat. No. Des. 963,695, which is a continuation of application No. 29/787,422, filed on Jun. 7, 2021, now Pat. No. Des. 949,902, which is a continuation of application No. 29/763,338, filed on Dec. 22, 2020, now Pat. No. Des. 921,689, which is a continuation of application No. 29/705,208, filed on Sep. 10, 2019, now Pat. No. Des. 911,382, which is a continuation of application No. 29/649,904, filed on Jun. 3, 2018, now Pat. No. Des. 860,242.

(57) **CLAIM**

The ornamental design for an electronic device with graphical user interface as shown and described.

DESCRIPTION

FIG. 1 is a front view of a display screen or portion thereof with graphical user interface showing the claimed design; and,

FIG. 2 is a front view of an electronic device having a display screen with the graphical user interface of FIG. 1 applied to the display screen.

The broken lines in the figures show a display screen or portion thereof, or an electronic device having a display screen, and form no part of the claimed design.

1 Claim, 2 Drawing Sheets
